UNITED STATES PATENT OFFICE.

JULIUS PETERSEN, OF ST. LOUIS, MISSOURI.

WINDOW-SHADE BRACKET.

SPECIFICATION forming part of Letters Patent No. 782,174, dated February 7, 1905.

Application filed October 10, 1904. Serial No. 227,922.

To all whom it may concern:

Be it known that I, JULIUS PETERSEN, a citizen of the United States, and a resident of the city of St. Louis, State of Missouri, have invented certain new and useful Improvements in Window-Shade Brackets, of which the following is a specification containing a full, clear, and exact description, reference being had to the accompanying drawings, forming a part hereof.

My invention relates to improvements in window-shade brackets; and it consists of the novel features herein shown, described, and claimed.

15 In the drawings, Figure 1 is a sectional elevation on the line 1 1 of Fig. 2 and looking in the direction indicated by the arrow. Fig. 2 is a top plan view as seen looking in the direction indicated by the arrow 2 in Fig. 1.

20 Fig. 3 is a perspective, upon a reduced scale, of a window-shade bracket embodying the principles of my invention. Fig. 4 is a horizontal sectional detail on the line 4 4 of Fig. 1 and looking in the direction indicated by the arrow.

25 Referring to the drawings in detail, the bearing-block 5 has a horizontal rectangular opening 6, and attaching-plates 7 and 8 extend upwardly and downwardly from the bearing-block, there being openings through said attaching-plates for the insertion of screws or nails. The adjusting-plate 9 is slidingly mounted through the opening 6 in the bearing-block 5, and the Hartshorn roller-bearing

30 10 is carried by one end of the plate. The bearings 10 support the window-shade, and the device is adjustable for different lengths of Hartshorn rollers by moving the plates 9 one way or the other through the bearing-block 5. The curtain-pole bearing 11 is held

35 a considerable distance in front of the shade-roller by the arm 12, said arm being formed

integral with the attaching-plate 13, and said attaching-plate is placed against the front face of the bearing-block 5, and the screw 14 is 45 inserted through the attaching-plate 13 and screw-seated in the front wall of the bearing-block 5, and the point of the screw engages the plate 9 to hold the plate in its adjusted position. 50

Care must be taken to cut the screw 14 exactly to the right length, so that as it tightens up against the attaching-plate 13 it will also tighten against the plate 9. Flanges 15 and 16 extend from the attaching-plate 13 to 55 engage the side edges of the bearing-block 5, and a flange 17 extends from the top of the attaching-plate 13 to engage the top of the bearing-block 5, so as to hold the attaching-plate 13 in line with the bearing-block. 60

The operation is obvious.

I claim—

In a window-shade bracket: the bearing-plate 5 having the horizontal rectangular opening 6; the attaching-plates 7 and 8 extending upwardly and downwardly from the bearing-block; the adjusting-plate 9 slidingly mounted in the opening 6; the roller-bearing 10 carried by the adjusting-plate; the curtain-pole bearing 11; the arm 12 supporting the 70 pole-bearing; the attaching-plate 13 at the opposite end of the arm 12 against the bearing-block 6; and the screw 14 inserted through the attaching-plate and screw-seated in the bearing-block 5 to hold the attaching-plate 75 13 and the adjusting-plate 9 in position.

In testimony whereof I have signed my name to this specification in presence of two subscribing witnesses.

JULIUS PETERSEN.
